DESIGN FOR A COMBINED SWITCH AND FUSE PANEL BOARD

Harrison J. L. Frank, Detroit, Mich.

Application February 23, 1935, Serial No. 55,563

Term of patent 7 years

To all whom it may concern:

Be it known that I, Harrison J. L. Frank, a citizen of the United States and a resident of Detroit, county of Wayne, Michigan, have invented a new, original, and ornamental Design for a Combined Switch and Fuse Panel Board, of which the following is a specification, reference being had therein to the accompanying drawing.

In the accompanying drawing,

The figure is an isometric view of a combined switch and fuse panel board, showing my new design.

The panel is the dominant feature of my design.

I claim:

The ornamental design for a combined switch and fuse panel board, substantially as shown and described.

HARRISON J. L. FRANK.
